UNITED STATES PATENT OFFICE.

GEORGE H. WHITTINGHAM, OF BALTIMORE, MARYLAND.

AUTOMATIC CIRCUIT-CONTROLLER.

SPECIFICATION forming part of Letters Patent No. 662,480, dated November 27, 1900.

Application filed March 19, 1900. Serial No. 9,206. (No model.)

To all whom it may concern:

Be it known that I, GEORGE H. WHITTINGHAM, a citizen of the United States, residing at Baltimore, in the State of Maryland, have 5 invented certain new and useful Improvements in Automatic Circuit-Controllers, of which the following is a full, clear, and exact description.

This invention relates to automatic circuit-controllers, the object being to provide means for closing and opening a circuit automatically as necessity arises and for accomplishing this by means whereby a predetermined inactive period may be caused to elapse between the moments of opening and closing the circuit. For instance, in driving an electric pump to compress air or gas a circuit-controller for the pump, which acts automatically in response to the pressure of the air or 10 gas, ordinarily opens the circuit when the pressure reaches the maximum and immediately closes it if a reduction of pressure takes place even to a very slight degree. In a system in which the pressure is rapidly utilized such a circuit-controller would be almost constantly vibrating at the contacts; and it is the object of my invention to provide a circuit-controller which after opening the circuit when the maximum pressure is 15 reached will hold it open until the pressure is diminished to a predetermined extent, whereupon the circuit is closed and the pressure again augmented.

In describing my invention I have assumed, 20 for example, a system in which an electric motor is used to drive a pump to compress or force the air or gas into a tank and have equipped a pressure-gage which connects with the tank with two cut-outs which are 25 adjusted to act successively upon two circuits shunting the main circuit-controller. One of these shunt-circuits is provided with a second cut-out operated by the main circuit-controller. While either of these shunts is closed 30 the main circuit-controller is deenergized and the consumption-circuit intact. The shunt containing the two cut-outs being the last one to be opened at the gage will when opened cause the main circuit-controller to be energized, which will thereupon make a second break in said shunt and open the consumption-circuit. If now the said shunt closes at

the gage, it will still remain open at the second cut-out and the main circuit-controller will not be deenergized until the first shunt containing the single cut-out at the gage is closed. 55

In the accompanying drawing the figure is a diagrammatical representation of the circuits and apparatus necessary to illustrate my invention. 60

Referring to the drawing by letters and figures, A and B respectively indicate supply-mains, across which is connected a circuit *a b*, supplying an electric motor or other translating device, which motor we will assume operates a pump to store air or gas in a tank. G indicates a pressure-gage subjected to the pressure in said tank. 65

D is an electromagnet in the form of a solenoid whose core *s* carries a bridging conductor *s'*, adapted to connect and disconnect two contacts *c'* and *c²* in the motor-circuit *a b*. The solenoid is for convenience connected across mains A B in a circuit 1 2, containing suitable resistance R. 70

Referring again to the gage G, it will be seen to consist of a curved tube *g*, to the free ends of which are hinged two arms *i* and *j*, respectively, which are adapted to connect and disconnect with contacts *i'* and *j'*, respectively. Two springs *p* and *p'* are attached at one end to a post *q* and at their other ends, respectively, to the two arms *i'* and *j'*, tending to hold said arms against their contacts. Two adjusting-screws *r* and *r'*, working in a post *r²*, bear against the arms *i* and *j* and serve as fulerums, upon which said arms will turn when the curved tube *g* straightens or flexes by reason of a variation of pressure therein. 75

From the wire 1 a shunt-circuit leads around the solenoid by way of wire 3, post *q*, spring *p'*, arm *j*, contact *j'*, and wire 4 to wire 2. A second shunt around the solenoid leads by wire 3, post *q*, spring *p*, arm *i*, contact *i'*, 80 wire 5, and across the contacts *c'* and *c²* to wire 2, and thus contains two cut-out points. 90

The operation is as follows: Let us assume, for illustration, that the allowed variation of pressure in the tank is five pounds, which 100 means that the adjusting-screws *r* and *r'* are set so that the pressure may vary within the limits of five pounds before both of the arms *i* and *j* will connect with or disconnect from

their contacts. Let us also assume that the pressure for the present is at or below the minimum side of the five pounds, under which condition both arms i and j are against their respective contacts, the contacts c' and c^2 being bridged and the motor running. When the pressure rises beyond the minimum side of the five-pound limit, the straightening of tube g causes the arm j to break connection 3 with its contact and open the shunt-circuit 4. This will make no change in the condition of the system, since the current will still have a path around the solenoid through the shunt-circuit, and the motor will continue. When the pressure rises to the maximum side of the five-pound limit, the arm i will leave its contact and open the second shunt-circuit, thus causing current to flow through the solenoid, which thereupon lifts 15 its armature and opens the circuit of the motor across the contacts c' and c^2 and at the same time makes a second opening in the second shunt. Now if the pressure immediately lowers, the arm i at once renews its connection with contact i' ; but the shunt which this connection formerly opened is not now closed thereby, because of the opening at c' c^2 . The result is that the pressure may continue to lower to the minimum side of the 20 five-pound limit, at which point the arm j will connect with its contact j' and close shunt 3 4. The current will then flow over this shunt and avoid the solenoid, which becomes deenergized and allows its armature to fall and bridge the contacts c c^2 , whereupon the motor again starts. This arrangement of two shunts around the circuit-controller, with a cut-out in each and a second cut-out in one of them, therefore insures a 25 positive action of the main circuit-controller and affords means for predetermining the period of inactivity of the circuit-controller.

The interval of inactivity of the main solenoid may be adjusted from zero to any desired maximum by simply setting the screws 40 r and r' .

Having described my invention, I claim—

1. The combination with a circuit-controller of two shunt-circuits around the same, 45 a cut-out in each shunt, one of which is operated by the circuit-controller, substantially as described.

2. The combination with a circuit-controller of two shunt-circuits around the same,

one shunt-circuit containing one cut-out and 55 the other containing two cut-outs, substantially as described.

3. The combination with a circuit-controller of two shunt-circuits around the same, 60 one shunt-circuit containing one cut-out and the other containing two cut-outs, one of the latter being operated by the circuit-controller.

4. The combination with a circuit-controller, of two shunt-circuits around the 65 same, one shunt-circuit containing one cut-out and the other containing two cut-outs, and a gage adapted to operate one cut-out in each shunt-circuit, substantially as described.

5. The combination with a circuit-controller, of two shunt-circuits around the same, 70 one shunt-circuit containing one cut-out and the other containing two cut-outs, and a gage adapted to operate successively one cut-out in each shunt-circuit, substantially as described.

6. The combination with a circuit-controller, of two shunt-circuits around the same, one shunt-circuit containing one cut-out and the other containing two cut-outs, a gage 80 adapted to operate one cut-out in each shunt-circuit and means for predetermining the interval between the operations of said cut-outs, substantially as described.

7. The combination with a circuit-controller, of two shunt-circuits around the same, 85 one shunt-circuit containing one cut-out and the other containing two cut-outs, one of the latter being operated by the circuit-controller, a gage adapted to operate one cut-out 90 in each shunt-circuit and means for predetermining the interval between the operation of said cut-outs, substantially as described.

8. The combination with a circuit-controller, of a pressure-gage whose movable element is a curved tube, two arms hinged at one end to the free end of said tube, and at the other adapted to control respectively two circuits shunting said circuit-controller, and means for altering the angular relation of the 95 arms, substantially as described.

In witness whereof I subscribe my signature in presence of two witnesses.

GEORGE H. WHITTINGHAM.
